TELESCOPIC COLUMN FOR X-RAY APPARATUS

William H. Amor, Jr., Auburn Township, Robert J. Steffek, Wickliffe, and Kenneth E. Wagner, Richmond Heights, Ohio, assignors to Picker Corporation, Cleveland, Ohio

Filed Nov. 21, 1973, Ser. No. 418,054

Term of patent 14 years

Int. Cl. D24—01

U.S. Cl. D83—1 H

Fig. 1

Fig. 2

FIG. 1 is a front perspective view of the telescopic column for X-ray apparatus showing our new design; and

FIG. 2 is a top plan view of the telescopic column for X-ray apparatus of FIG. 1.

We claim:

The ornamental design for a telescopic column for X-ray apparatus, as shown.
